UNITED STATES PATENT OFFICE.

EDWIN C. PALMER, OF CLEVELAND, OHIO.

STAMP-AFFIXING MACHINE.

SPECIFICATION forming part of Letters Patent No. 484,448, dated October 18, 1892.

Application filed September 28, 1891. Serial No. 406,996. (No model.)

To all whom it may concern:

Be it known that I, EDWIN C. PALMER, a citizen of the United States, and a resident of Cleveland, county of Cuyahoga, and State of Ohio, have invented certain new and useful Improvements in Stamp-Affixing Machines, of which the following is a specification, the principle of the invention being herein explained and the best mode in which I have contemplated applying that principle, so as to distinguish it from other inventions.

The annexed drawings and the following description set forth in detail one mechanical form embodying the invention, such detail construction being but one of various mechanical forms in which the principle of the invention may be used.

In the annexed drawings, Figure I represents a perspective view of my improved stamp-affixing device; Fig. II, a top plan view of the device with the top removed; Fig. III, a longitudinal section on the line III III, Fig. II; Fig. IV, a vertical cross-section on the line IV IV, Fig. III; Fig. V, a vertical cross-section on the line V V, Fig. III; and Fig. VI, a perspective view of the stamp-carrier.

In the drawings the letter A indicates a casing, which in this case is illustrated as constructed to hold two denominations of stamps, although the several mechanisms may of course be duplicated as many times as desired to provide for a larger number of denominations of stamps.

As the devices for picking up, conveying, and affixing the stamps are the same for each denomination, I shall, as far as the description of such elements goes, confine myself to describing one set.

The principle upon which my device is based is the ability of a resinous, vitreous, or similar idioelectric body to attract and support a light body—such as a bit of paper—when electrified by being rubbed upon a surface of wool, silk, or cat's skin. In my device I make said body in the shape of a knob or button B, preferably rectangular and of a size slightly larger than a postage-stamp. Said knob is secured upon the end of a shank b, having a handle B' and guided in a longitudinal slot a in the top of the casing. The shank has a cross-bar b', which forms a guide-head for the device, which I shall term the "stamp-car-

rier," as said guide-head travels in guides C at both sides of the carrier and is rigidly supported in the casing. Said guides consist of 55 rubbing portions c, which are parallel with the rubbing-surface of a rubber D, preferably yieldingly supported in the casing upon springs d, and against which the carrier may be rubbed to be electrified or charged with 60 frictional electricity, the distance between the rubbing-surface of said rubber and the rubbing portions of the guides being less than the distance between the attractive surface of the stamp-carrier and its cross-bar, so that said 65 rubber may be depressed by said stamp-carrier against the tension of its springs, and thus have frictional contact with the same. The rubbing portions of the guides are deflected into picking portions c', (shown vertical in 70 the drawings,) which portions direct the carrier to the stamp-receptacle E. This receptacle is shown in the form of a drawer E', extending transversely through the casing and provided with a suitable lock and with downwardly-yielding spring-cushioned stamp-retaining frames e, within which the stamps are arranged in a pile, so that the carrier may be depressed and depress the spring-frame until it touches the uppermost stamp in the pile 80 and attracts it. The guides are extended forward and deflect into affixing portions c'', (shown vertical in the drawings,) which portions direct the carrier toward a cushion or support F, upon which the envelope, which 85 has previously been moistened, rests. When the carrier and stamps are depressed upon the moistened envelope, the stamp will adhere and the carrier may be moved back to be again electrified and to again carry a stamp 90 forward.

As it is desirable to keep an account of the stamps used, I prefer to provide a registering device which will register the number of stamps used of each denomination and register and indicate the total amount of stamps used in dollars and cents. I therefore journal a disk G, having numbers from "1" to any desired number serially marked upon its periphery at the side of each guideway, and provide a slot a' in the top of the casing of a sufficient size to disclose one number. A ratchet-wheel G' is secured at the side of the register-disk and has a number of teeth cor-

responding to the numbers upon the disk. A stationary pawl g engages the ratchet-wheel and serves as a stop-pawl, and a movable pawl g' is pivoted upon a lever G^2 , the forward arm of which extends forward to be engaged and depressed by a lip b^2 upon the carrier, while the rear arm of the lever has a spring g^2 connected to it to force said arm and the pawl downward after the forward end 10 has been depressed and again released.

By means of this device each depression of the stamp-carrier and consequent affixion of a stamp will be registered and indicated. The registering and indicating mechanism for the amounts in money value is arranged in the rear end of the casing and consists of a shaft H , having a disk H' secured upon it, said disk having numerals from "0" to "99" marked upon its periphery. Ratchet-wheels H^2 are secured 15 upon the same shaft and have teeth corresponding in number to the numerals upon the disk, the wheel connected to the register for the one-cent stamps having, for example, one hundred teeth, the one connected to the register for the two-cent stamps having fifty, &c. The ratchet-wheels are engaged by stop-pawls h and by pawls h' upon levers H^3 , connected at their forward ends to the levers of the corresponding stamp-registers and provided with 20 springs h^2 for returning them to their normal positions. The teeth of the ratchet-wheels and the throw of the levers are so constructed and gaged that the register-disk is revolved the space of one number each time the one-cent-stamp register is operated, the space of 25 two numbers each time the two-cent-stamp register is operated, &c., the disk thus registering and indicating through an opening a^3 in the casing the value, in cents, of the stamps 30 used.

For the purpose of enabling the register to indicate the amount of stamps used in greater amounts than one dollar I secure a cog-wheel H^4 upon the shaft of the cent-registering disk, which wheel meshes with a cog-wheel J , having the same diameter and number of cogs and secured upon a shaft J' , journaled parallel to shaft H . Said shaft has a wheel J^2 secured upon it and provided with one cog 45 j , which meshes with a cog-wheel K , loose upon the shaft H and secured to a dollar-registering disk K' , having figures upon its periphery corresponding to the cogs of the wheel and showing through the opening a^3 , said disk being arranged at the side of the cent-registering disk. It is obvious that each revolution 50 of the cent-registering disk and its shaft H will cause one revolution of the shaft J' , and consequently a movement forward of one 55 space of the dollar-registering disk.

The casing is formed with a slot or opening a^4 at the cushion for the envelope, so that the envelope or letter may be inserted beneath the stamp-carrier, and dampening-pads 60 L are supported at the side of said slot, so that the corners upon which the stamps are

to be affixed may be moistened by simply passing the envelope or letter beneath the pad into the slot.

Other modes of applying the principle of my invention may be employed for the mode herein explained. Change may therefore be made as regards the mechanism herein set forth, provided the principles of construction respectively recited in the following claims 75 are employed.

I therefore particularly point out and distinctly claim as my invention—

1. In a stamp-affixing machine, the combination of a yieldingly-supported rubbing-pad, 80 an idioelectric stamp-carrier, and a guide for the latter arranged parallel with the rubbing-surface of the rubbing-pad, substantially as set forth.

2. In a stamp-affixing machine, the combination of a yieldingly-supported rubbing-pad, 85 a guide parallel with the rubbing-surface of said pad, and an idioelectric stamp-carrier having a cross-bar traveling in said guides and at a distance from the attractive surface 90 of the carrier greater than the normal distance between the rubbing-surface of the pad and the guide, substantially as set forth.

3. In a stamp-affixing machine, the combination of a closed casing, a stamp-receptacle 95 in the same, a letter or envelope support in the casing, a stamp-carrier, a guide for the latter between the stamp-receptacle and the support, and a register having a lever projecting toward the support in the path of the 100 stamp-carrier, so as to be operatively engaged by the latter when it is brought against the support, substantially as set forth.

4. In a stamp-affixing machine, the combination of a closed casing having an opening 105 for the insertion of envelopes or letters, stamp-carriers, each carrier movable in said casing toward and from said opening, and a drawer provided with means for locking it in said casing and having stamp-receptacles corresponding to and registering with the carriers and the opening, substantially as set forth.

5. In a stamp-affixing machine, the combination of a set of stamp-affixing devices, each device affixing one denomination of stamps, a 115 register indicating amounts in money, and intermediate mechanism connected to said affixing devices and register and constructed to move the money-register in degrees corresponding to the value of the stamps affixed, 120 substantially as set forth.

6. In a stamp-affixing machine, the combination of a closed casing, a rubbing-pad, a stamp-receptacle, and an envelope-support arranged within said casing, and a stamp-carrier consisting of a handle guided in said casing, and a knob of idioelectric material, 125 substantially as set forth.

7. In a stamp-affixing machine, the combination of a rubbing-pad, a stamp-receptacle, 130 and an envelope-support, all arranged in a series, with an idioelectric stamp-carrier and

a guide for the same arranged to guide said carrier over and to said pad, receptacle, and support, substantially as set forth.

8. In a stamp-affixing machine, the combination of a rubbing-pad, a stamp-receptacle, and an envelope-support, all arranged in a series, with an idioelectric stamp-carrier and a guide for the latter, arranged parallel with the rubbing-pad and with deflections to the stamp-receptacle and envelope-support, substantially as set forth.

9. In a stamp-affixing machine, the combination of a closed casing having an opening for the insertion of an envelope or letter, a locked stamp-receptacle within said casing, and a stamp-carrier movable in said casing, substantially as set forth.

10. In a stamp-affixing machine, the combination of a set of stamp-affixing devices, each device affixing one denomination of stamps, a set of registers, each register connected to

be operated by one affixing device and to register the number of stamps affixed, a register indicating amounts in money, and connections between said register and the set of stamp-registers, constructed to move the money-register in degrees corresponding to the value of the stamps registered, substantially as set forth.

11. In a stamp-affixing device, the combination of a stamp-receptacle, an envelope-support, a stamp-carrier, and a register having an arm projecting in the path of the stamp-carrier, substantially as set forth.

In testimony that I claim the foregoing to be my invention I have hereunto set my hand this 22d day of Sepember, A. D. 1891.

EDWIN C. PALMER.
